UNITED STATES PATENT OFFICE.

ALBERT H. HENDERSON, OF BALTIMORE, MARYLAND.

PROCESS FOR EXTRACTION OF COPPER FROM THE MATTE.

No Drawing. Application filed May 9, 1921, Serial No. 467,937. Renewed April 21, 1925.

To all whom it may concern:

Be it known that I, ALBERT H. HENDERSON, citizen of the United States, residing at Baltimore and State of Maryland, have 5 invented certain new and useful Improvements in Processes for Extraction of Copper from the Matte, of which the following is a specification.

My invention relates to the treatment of 10 matte for the extraction of metal, and it relates particularly to the treatment of copper matte for the extraction of copper therefrom.

An object of my invention is to render 15 the copper readily soluble in acids so that it may be easily removed from the matte.

Another object of my invention is to so treat the matte that the copper may be extracted therefrom in a form substantially 20 free from impurities.

Another object of my invention is to increase the percentage of copper which may be recovered from the matte over the present percentage yield obtained by the methods commonly employed.

A still further object of my invention is to accomplish the above outlined objects quickly and with a small cost.

With these and other objects in view my 30 invention consists in the process to be hereinafter set forth and claimed, with the understanding that the chemical equivalents of the compounds employed may be used, without avoiding the spirit of the invention, and that the precise temperatures employed may be varied in accordance with the quantity or quality of material treated.

In former processes it has been necessary to subject the matte to a long series of 40 steps which rendered these processes expensive and tedious. Where the process has been carried out in few steps, the temperatures necessary to effect the desired change in the copper have been such that a portion 45 of the copper has been volatilized and lost.

In my process the ore is crushed and treated in accordance with the ordinary method to form the substance commonly 50 called copper matte. This copper matte is then crushed to form a powder. The powder is mixed with powdered alkali carbonate, an oxidizing agent and fluxing agents. These are mixed together and the 55 whole is put into a receptacle and heated. The heat is preferably applied at the bot-

tom of the receptacle thus keeping the surface of the charge from direct contact with flame or super-heated gases. The mixture is preferably heated to a temperature which I designate, incipient red, that is to say, slightly lower than cherry red. Care should be exercised to prevent the mixture from being heated to a cherry red for at that heat the copper starts to volatilize and metal is lost thereby. By preventing the flame or super-heated gases from coming in contact with the surface of the mixture being heated, volatilization of the copper is likewise prevented.

It is to be understood that I may employ cherry red heat and may allow the flame or super-heated gases to play on the surfaces of the mixture under treatment, but I have found it more economical and satisfactory to carry out my process at a reduced temperature.

One particular combination of substances that I have found produces especially good results is to employ sodium carbonate for the alkali carbonate, a mixture of alum and borax as fluxing agents and chloride of lime as the oxidizing agent. These compounds are of low cost and readily obtainable in the open market.

As an example, in a low grade of copper matte containing approximately 46.50 per cent copper, 24.03 per cent sulphur, .077 per cent arsenic, .52 per cent silica, and 17.03 per cent iron, I have employed successfully the following composition of ingredients: With one hundred parts of ore I combine twenty-four parts of chloride of lime (essentially hypo-chlorite), twenty parts of alum, ten parts of borax, and five parts of sodium carbonate. The results obtained from a heat treatment of this mixture give a very high yield of copper.

The function of the alkali carbonate in the mixture is to remove the impurities having acid properties, such as silica and the various silicates. The proportion of alkali carbonate employed depends largely on the percentage of these substances in the type of ore treated.

While I prefer to use as oxidizing agent chloride of lime other oxidizing agents may be employed, such as other hypo-chlorites of the alkalies or of the alkaline earths. However, because chloride of lime may be readily obtained at small cost I generally employ the same.

The proportion of ingredients used depends on the characteristics of the matte treated. In certain kinds of matte I find that the proportion of fluxing agents to the 5 other ingredients has to be radically increased, and in other instances the proportional quantity of alkali carbonate or of oxidizing agents is varied.

After treating the matte at incipient red 10 heat for a period of time which can be determined only by experimentation for each particular grade of matte treated, I allow the mixture to cool and extract the copper therefrom with an acid in accordance with 15 the usual method employed. As is customary I ordinarily employ sulphuric acid, but this part of the process comprises no part of my invention.

I have devised a method of treating copper 20 matte to render the copper readily extractable which is cheap, and gives a high yield of copper. Moreover, my process can be quickly carried out, thus effecting a large saving of time, which has the effect of further 25 decreasing the expense of production.

It is to be understood that the proportions of ingredients used may be varied widely, depending on the type of ore treated, and that while I may have to employ 30 relatively large quantities of one of the ingredients in any particular treatment, in another treatment the quantity of that ingredient may be much less, though the amount of ore treated is the same in both 35 cases.

While I have not described all the possible modifications of my invention I desire that it be limited solely by the appended claims and the scope of the prior art.

40 I claim as my invention:

1. A method of treating copper matte to render the copper easily extractable comprising the step of subjecting the matte to the action of an alkali carbonate, fluxing 45 agents and a hypo-chlorite of alkali, at a raised temperature.

2. A method of treating copper matte to render the copper easily extractable, comprising the step of subjecting the matte to the action of an alkali carbonate, fluxing 50 agents and a hypo-chlorite of the alkali earths, at a raised temperature.

3. A method of treating copper matte to render the copper easily extractable, comprising the step of subjecting the matte to the action of an alkali carbonate, fluxing 55 agents and a mixture of the hypo-chlorite of alkali and the alkali earths, at a raised temperature.

4. A method of treating copper matte comprising the step of subjecting the matte to the action of an alkali carbonate, alum 60 and a hypo-chlorite of alkali, at a raised temperature.

65 5. A method of treating copper matte to

render the copper easily extractable, comprising the step of subjecting the matte to the action of an alkali carbonate, borax and a hypo-chlorite of alkali, at a raised temperature.

6. A method of treating copper matte to render the copper easily extractable, comprising the step of subjecting the matte to the action of an alkali carbonate, fluxing 70 agents containing alum and a hypo-chlorite of alkali, at a raised temperature.

7. A method of treating copper matte to render the copper easily extractable comprising the step of subjecting the matte to the action of an alkali carbonate, alum and 75 a hypo-chlorite of the alkali earths, at incipient red heat.

8. A method of treating copper matte to render the copper easily extractable, comprising the step of subjecting the matte to the action of an alkali carbonate, borax and a hypo-chlorite of the alkali earths, at incipient 80 red heat.

9. A method of treating copper matte to render the copper easily extractable, comprising the step of subjecting the matte to the action of an alkali carbonate, a mixture 85 of alum and borax, and a hypo-chlorite of the alkaline earths, at incipient red heat.

10. A method of treating copper matte to render the copper easily extractable, comprising the step of subjecting the matte to the action of an alkali carbonate, a fluxing 90 agent containing alum and a hypo-chlorite of the alkaline earths, at a raised temperature.

11. A method of treating copper matte to render the copper easily extractable, comprising the step of subjecting the matte to the action of an alkali carbonate, a fluxing 105 agent containing alum, and a mixture of the hypo-chlorites and alkali and the alkaline earths, at a raised temperature.

12. A method of treating copper matte to render the copper easily extractable, comprising the step of subjecting the matte to the action of an alkali carbonate, a fluxing 110 agent containing borax and a mixture of the hypo-chlorites of alkali and the alkaline earths, at a raised temperature.

13. A method of treating copper matte to render the copper easily extractable, comprising the step of subjecting the matte to the action of an alkali carbonate, a fluxing 120 agent containing alum, borax and a mixture of the hypo-chlorites of alkali and the alkaline earths, at incipient red heat.

14. A method of treating copper matte to render the copper easily extractable, comprising the step of subjecting the matte to the action of an alkali carbonate, a fluxing 125 agent containing alum, and a mixture of the hypo-chlorites of alkali and the alkaline earths, at a raised temperature.

15. A method of treating copper matte to

render the copper easily extractable comprising the step of subjecting the matte to the action of sodium carbonate, alum, borax and chloride of lime at incipient red heat.

5 16. A method of treating copper matte to render the copper easily extractable, comprising the step of subjecting the matte to the action of an alkali carbonate, fluxing agents and an oxidizing agent, at a raised 10 temperature.

17. A method of treating copper matte to render the copper easily extractable, comprising the step of subjecting the matte to the action of an alkali carbonate, alum and 15 an oxidizing agent at incipient red heat.

18. A method of treating copper matte to render the copper easily extractable, comprising the step of subjecting the matte to

the action of an alkali carbonate, alum and borax and an oxidizing agent, at incipient 20 red heat.

19. A method of treating copper matte to render the copper easily extractable, comprising the step of subjecting the matte to the action of an alkali carbonate, borax and 25 an oxidizing agent, at incipient red heat.

20. A method of treating copper matte, to render the copper easily extractable, comprising the step of subjecting the matte to the action of an alkali carbonate, a fluxing 30 agent containing alum and an oxidizing agent, at a raised temperature.

In testimony whereof I affix my signature.

ALBERT H. HENDERSON.
